CAN-FEEDING MECHANISM

Ernest P. Tarot, San Jose, Calif., assignor to Food
Machinery and Chemical Corporation, a cor-
poration of Delaware

Application September 21, 1946, Serial No. 698,412

6 Claims. (Cl. 198—33)

1

This invention relates to can feeding mechanisms and more particularly to conveyors for delivering cans or similar bodies to the pocketed valve turrets of continuous canned goods cookers.

An object of the invention is to provide an improved mechanism for feeding cans to moving receivers so that the cans are accurately and positively delivered to the receivers without damage or shock.

Another object of the invention is to provide an improved mechanism for feeding cans to the rotatable feed valves of continuous cookers and the like, in which the cans are conveyed toward the feed valves by a fixed guide arranged to receive the cans in one position, to convey the cans toward the feed valves in such position, and having means for turning the cans for delivery to the feed valves in a predetermined position.

Still another object of the invention is to provide a can feeding mechanism of the above type in which the cans are moved through the fixed guide by a chain having can moving elements guided in the same relative position through the fixed guide and the can turning means.

A further object of the invention is to provide a can feeding mechanism of simple construction and efficient operation which is non-clogging and requires no attention during operation.

Another object of the invention is to provide a can orienting device for can feeding mechanisms for turning the cans through a predetermined angle during movement of the cans therethrough.

A further object of the invention is to provide a can twister for turning the cans through a predetermined angle in which the cans are under control at all times.

Another object of the invention is to provide can feeding mechanism for turning cans from one position to another position, in which the cans gravitate through the mechanism and the movement of the cans through the mechanism is controlled at all times.

Still a further object of the invention is to provide an improved can conveyor having a fixed can guide formed with slots and a conveyor chain arranged outside of the guide and having can moving elements extending through the slots, with which is combined a can twister for turning the cans from one position to another position and having a slot extending lengthwise thereof for guiding the can moving elements through the twister in the same relative position as the position of the elements in the slots of the guide.

2

These and other objects and advantages of the invention will become apparent from the following description and accompanying drawings, in which:

- 5 Fig. 1 is a plan view of a portion of the inlet end of a pressure cooker showing the can feeding mechanism of the present invention applied thereto;
- 10 Fig. 2 is a vertical sectional view taken along the line 2—2 of Fig. 1;
- Fig. 3 is a vertical sectional view taken along the line 3—3 of Fig. 1;
- Fig. 4 is a horizontal sectional view taken along the line 4—4 of Fig. 3;
- 15 Fig. 5 is an enlarged vertical sectional view taken along the line 5—5 of Fig. 1 showing the conveyor and the valve turret in one position;
- Fig. 6 is a view of a portion of the structure shown in Fig. 5 showing the conveyor and the valve turret in another position;
- 20 Figs. 7 to 13, inclusive, are horizontal sectional views taken along the lines 7—7 to 13—13, inclusive of Fig. 5, illustrating the detail construction of the can twister;
- 25 Fig. 14 is a horizontal sectional view taken along the line 14—14 of Fig. 6;
- Fig. 15 is an enlarged vertical transverse sectional view taken along the line 15—15 of Fig. 2; and
- 30 Fig. 16 is an enlarged vertical transverse sectional view taken along the line 16—16 of Fig. 2.
- Referring to Figs. 1, 2, 3, and 5 of the drawings, the conventional form of continuous canned goods cooker in connection with which the present invention has been illustrated herein, comprises a cooking chamber 11 formed of a hollow cylindrical shell 12 closed at its ends. Since these cookers are well known in the art, only the portion of the cooker at the inlet or the end through which the cans are delivered to the chamber 11 for processing is shown. As is customary in these cookers, the interior wall of the shell 12 is provided with a continuous spirally arranged guide rail 13 (Fig. 5) which forms a helical pathway for guiding the cans from the inlet to the outlet of the cooker. A reel, made up of a plurality of spider wheels 14, provided with L-shaped rails 15, is mounted upon a rotatable shaft 16 (Figs. 1 and 3), longitudinally extending through the chamber 11.
- 35 The cans are delivered into the cooker by means of a feed valve device 21 comprising a casing having a cylindrical wall 22 and end walls 23 and 24 which are detachably secured to the cylindrical wall 22 by means of bolts 25, as shown

in Fig. 1. The cylindrical wall 22 of the feed valve casing is formed with an inlet port or opening 26, and an outlet port or opening 27 (Fig. 5). The outlet opening 27 is disposed in registry with an opening 28 provided in the shell 12 of the cooker. The feed valve casing as a unit is secured to the shell 12 by means of bolts 29, as shown in Figs. 1, 3, and 5.

A valve turret 31 mounted on a shaft 32, rotates within the casing of the feed valve 21. The turret 31 has a series of pockets 33 (Fig. 5), formed in the periphery thereof for receiving the cans and for successively feeding them through the outlet opening 27 onto the L-shaped rails 15 of the reel within the chamber 11. The pockets 33 are separated by radially disposed walls 34, and have a can supporting surface 35 that moves downwardly past the inlet opening 26 during rotation of the turret in the direction of the arrow 36, as shown in Fig. 5.

In cookers of the type herein shown, the shaft 32 is supported in bearings 37 (Fig. 1) so that the feed valve turret 31 is rotatable about a horizontal axis, and the pockets 33 are arranged to receive the cans so that the longitudinal axis of each can delivered to the turret is disposed substantially parallel with the longitudinal axis of the cooker. In the present instance, the inlet port or opening 26 is located in the wall 22 of the casing 21 at a point substantially in alignment with a line passing in a horizontal plane through the axis of rotation of the turret. This arrangement of the inlet opening 26 with respect to the axis of the valve turret 31 is somewhat different than has been the practice heretofore. In the cookers of the prior art to which the present invention is applicable, it was usually the custom to locate the inlet opening at some point in the casing of the feed valve above the axis of the turret, so that cans delivered by the conveyor to the feed valve would drop by gravity into the pockets of the turret as the pockets successively registered with the inlet opening during rotation of the turret. However, as herein shown, the inlet opening 26 has been arranged in the side of the feed valve casing at a point where the cans can be introduced into the pockets of the turret without dropping therein.

As shown in Fig. 1, the shaft 22 of the feed valve turret 31 is provided with a gear 42 keyed thereto and having its teeth in meshing relationship with the teeth of a gear 43 keyed to shaft 16. Shaft 16 is driven in well known manner from a suitable source of power (not shown) and from said driven shaft and gear 43, power is derived for driving all units of the mechanism of the present invention, in the manner to be herein-after described.

The can feeding mechanism of the present invention is especially adapted for feeding the cans to and placing them into the pockets 33 of the valve turret 31, and comprises in general a conveyor 45, which extends outwardly a suitable distance from the inlet end of the cooker to a convenient point (not shown) where the cans, after they have been filled and closed, are delivered in single file to the receiving end portion of the conveyor.

As shown in Fig. 1, the conveyor 45 is located at one side of the longitudinal axis of the cooker in proximity to the feed valve device 21. Preferably the conveyor is disposed substantially in a plane parallel to the longitudinal axis of the cooker. Heretofore, in some instances, it has

been the practice to arrange the can feeding conveyors in a plane disposed at right angles with respect to the longitudinal axis of the cookers. When the conveyors are thus disposed, they occupy considerable space and block the aisles between adjacent lines of cookers. When the conveyors are arranged parallel with the longitudinal axis of the cookers, such as is the arrangement of the conveyor 45 with the cooker 11, the aisles between adjacent lines of cookers will be unobstructed and also the aisles need not be as wide as the width of the aisles required when the conveyors are disposed at right angles to the longitudinal axis of the cookers. Another advantage in arranging the conveyor 45 parallel with the longitudinal axis of the cooker is that the filling and closing machines can be arranged substantially in alignment with the cooker and the cans fed in a plane parallel to the longitudinal axis of the cooker, thereby reducing to a minimum the amount of space required between adjacent lines of equipment on the cannery floor.

The conveyor 45 is adapted to move the cans in uniformly spaced apart relationship and delivers them one by one, successively, into the successive pockets 33 of the valve turret 31, the said conveyor and the said valve turret traveling in timed relation with respect to each other, both being driven directly from the same rotary member, i. e., shaft 32.

As shown in Figs. 1 and 5, the cans 46 may be cylindrical in form and may have a length somewhat greater than their diameter. The conveyor receives the cans 46 and transports them toward the feed valve device 21 with the longitudinal axis of each can arranged perpendicular or at right angles to the longitudinal axis of the pockets 33 of the valve turret 31. Means are provided in the conveyor, preferably at a point adjacent to the inlet opening 26, for turning the cans, in the manner to be hereinafter more fully described, so that each can will enter a pocket 33 with its longitudinal axis substantially parallel to the longitudinal axis of the pocket.

The conveyor 45 comprises a single endless double strand chain 48 which travels around a drive sprocket 49, Figs. 2 and 3, located in proximity to the feed valve 21. It will be understood that the chain 48 also travels around suitable guide means, such as a drum or sprocket (not shown) rotatably mounted at the can receiving end of the conveyor in well known manner. The sprocket 49 is fixed to a shaft 50 rotatably mounted in a bearing 51 formed in the long arm of a Y-shaped bracket 52. In addition to the long arm having the bearing 51, the bracket 52 has two short arms formed with bearings 53 and 54, respectively. Fixed to the short arm of the bracket 52 having the bearing 53 is another bracket 55 which is mounted on the shell 12 of the cooker so that the bracket 52 will be rigidly supported thereby.

The chain 48 is driven from the valve turret shaft 32 by the following mechanism: As shown in Figs. 1, 3, and 4, fixed to shaft 32 is a gear 56 which meshes with a gear 57 keyed to shaft 58 mounted in the bearings 53, 54 and also a bearing 59 of a bracket 60. Shaft 58 has a bevel gear 61 keyed thereto which gear meshes with a bevel gear 62 fixed to shaft 50 heretofore described. Thus, rotation imparted to the valve turret shaft 32 by gears 43 and 42 is transmitted to the shaft 50 on which is mounted the sprocket 49. In this manner the conveyor chain 48 is simultaneously

operated in timed relation with the valve turret 31.

The chain 48 is composed of links 66 pivoted together by pins 67. Each link of the chain is formed of four bars of suitable length arranged in two sets of pairs side by side, and in order to maintain the bars of each pair spaced apart, rollers 68 are mounted on each pivot pin 67 between each pair of bars (Figs. 5 and 6). Mounted intermediately of each third link and projecting laterally from the chain is a stud 70 which constitutes a can carrying and propelling member or flight. The construction and arrangement of the parts is such that the studs 70 are rigidly supported by the chain and are uniformly spaced apart so as to provide can receiving spaces therebetween. Also, the studs are preferably formed from round bars of a length determined by the length of the cans so that they will be at least coextensive of the cans being transported by the conveyor. The reason for utilizing round studs is to provide a single line or point of contact between the studs and the cans.

As shown in Fig. 2, the upper flight of the chain 48 is associated with an upper fixed guide portion of the conveyor generally indicated at 71, and the lower flight of the chain 48 is associated with a lower fixed guide portion of the conveyor generally indicated at 72. The two fixed guide portions 71, 72 of the conveyor may be rigidly tied together by bars 73, Fig. 2, arranged at suitable intervals throughout the length of the entire conveyor structure, and the portion of the conveyor structure herein illustrated is rigidly secured to the cooker, as indicated by bolts 74, Figs. 1 and 5.

As shown in Fig. 2, intermediate the length of the conveyor 45 a section may be substantially horizontally disposed in a plane a suitable distance above the cooker. Directly over the inlet feed valve device 21, the upper fixed guide portion 71 of the conveyor is formed with an arcuate portion 75 which extends downwardly from the horizontal portion. Below the arcuate portion 75 there is a substantially vertical portion 76 which has a flange 77 at its lower end.

The horizontal section of the upper fixed guide 71 of the conveyor is substantially of channel form in cross section, as shown in Fig. 15, consisting of a flat bottom can supporting member 78, preferably formed of sheet metal, and sides 79, 80 upstanding from the longitudinal side edges of the can supporting member 78. The horizontal section of the upper fixed guide 71 is open at the top, as shown in Figs. 1 and 15, and the channel form of said guide is continued in the arcuate portion 75 and the vertical portion 76. However, in order to prevent lateral displacement of the cans traveling down the portions 75 and 76 of the conveyor, the open portion of the channel is closed by an arcuate cover plate 81 which is secured to the sides 79 and 80 by means of bolts 82, as shown in Figs. 1 and 2.

The side 79 of the upper fixed guide 71 is formed of a pair of bars 83, 84 arranged in parallel spaced relation to each other so as to provide a slot 85 therebetween, and similarly the side 80 is formed of bars 86, 87, spaced apart to provide a slot 88 therebetween (Fig. 15). The studs 70 of the chain 48 are disposed in the slots 85, 88 so as to be guided thereby. The can supporting member 78 and the sides 79, 80 may be constructed in any suitable manner so that the slots 85, 88 will be continuous and unobstructed and thus permit free movement of the studs therein

throughout the entire length of the upper fixed guide 71.

Also formed as a part of the upper fixed guide 71, is a track for the chain 48 comprising a pair of angle bars 90, 91, both of which are disposed at one side of the fixed guide and arranged above and below the chain, as shown in Fig. 15. The angle bars 90, 91 are secured, respectively, to the two spaced bars 83, 84 of the side 79 so as to provide a space or slot 92 between them to receive the rollers 68. The angle bars 90, 91 are also mounted in spaced relation to the side bars 83, 84 by means of spacers 93, 94, the parts being secured together by bolts or machine screws 95. The purpose of the spacers 93, 94 is to provide a channel 96 extending longitudinally of the upper flight of the conveyor in registration with the slot 85. The channel 96 is arranged to receive a plurality of guide plates 97 on the chain 48. As shown in Figs. 2, 5, and 15, each guide plate 97 comprises a rectangular body which is mounted on a stud 70 and which is also perforated to receive pivot pins 67 at opposite sides of each stud. Thus each link 66 of the chain 48 which carries a stud 70 is reinforced by an additional bar in the form of the guide plate 97. These plates 97 retain the studs 70 in position perpendicular to the chain 48 during travel of the chain through the upper fixed guide 71 of the conveyor and downwardly through the portions 75 and 76 thereof.

The fixed guide 72 for the lower flight of the conveyor chain 48 is substantially of channel form in cross section, as shown in Fig. 16, consisting of a flat bottom chain supporting member 101 having upstanding sides 102. The member 101 and its sides 102 may be formed of sheet metal, and mounted on the member 101 in spaced relation to the sides 102 are bars 103, 104. These bars extend lengthwise of the fixed guide 72 and provide a support for the chain 48, the rollers 68 of said chain engaging the bar 103 and the outer end portions of the studs 70 resting upon the bar 104. The purpose of the bars is to keep the guide plates 97 from contacting the surface of the supporting member 101 so that the chain will move freely on its trackway.

As shown in Fig. 2, the fixed guide 72 extends from a point in proximity to the sprocket 49 upwardly for a suitable distance, and thence horizontally in substantially parallel relationship to the horizontal portion of the upper guide 71. From the left hand portion of the conveyor, as viewed in Fig. 2, the guides 71 and 72 may be inclined downwardly at a suitable angle toward the feed end of the conveyor (not shown).

At a suitable point above the inlet opening 26 the conveyor 45 is formed with a can twister, generally indicated at 111, Figs. 2, 3, and 5. The can twister comprises two separate vertically disposed sections 112, 113 which are secured to the flange 77 of the fixed guide 71 by bolts 114.

The interior of the section 112 is formed lengthwise thereof with a plurality of twisted surfaces 115, 116, 117, and 118, and the interior of the section 113 is formed with a plurality of twisted surfaces 120, 121, 122, and 123. The twisted surface 116 is disposed at right angles or perpendicular to the twisted surfaces 115 and 117 (Figs. 7 and 8), and the twisted surface 118 is disposed at right angles or perpendicular to the twisted surface 115 (Figs. 10, 11, 12, and 13). The twisted surface 121 is disposed at right angles or perpendicular to the twisted surfaces 120 and 122 (Figs. 7 and 8), and the twisted surface

123 is disposed at right angles or perpendicular to the twisted surface 120 (Figs. 10, 11, 12, and 13). The section 112 is also formed with plain faces 125, 126 arranged vertically along the sides thereof, and the section 113 is formed with plain vertical faces 127, 128 along the sides thereof. When the two sections 112, 113 are assembled in the manner shown in Figs. 7 to 13, inclusive, the faces 125, 126 are spaced from the faces 127, 128, respectively, a suitable distance to provide a vertical slot 130 between the sections through which slot the studs 70 of the chain 48 are adapted to freely pass. The slot 130 aligns with the slots 85, 88 of the fixed guide 71 and provides a straight line continuation thereof so that the studs 70 are guided in the same relative position through the twister 111 of the conveyor. If so desired, the walls of the sections 112, 113 having the twisted surfaces 116, 121, respectively, may have openings 132, 133 formed therein so that access may be had to the interior of the twister without dismantling the same.

The construction and arrangement of the parts of the twister 111 is such that a twisted can path is formed lengthwise thereof for the cans, the opposed surfaces 116, 121 of the sections 112, 113, respectively, being substantially parallel, and the opposed surfaces 115, 120 being substantially parallel. As shown in Fig. 7 at the upper end or can entrance of the twister, the two surfaces 116, 121 are disposed parallel with the longitudinal axis of the studs 70, and, as shown in Fig. 13, these two surfaces 116, 121 have been twisted so that at the lower or discharge end of the twister they are disposed substantially perpendicular or at right angles to the longitudinal axis of the studs 70. Thus the construction of the twister 111 is such that a spiral canway, substantially rectangular in cross section, is provided (see Figs. 7 to 13, inclusive), by which the cans are turned through an angle of approximately 90°. The overall dimensions of the canway thus provided in the can twister 111 are slightly greater than the size of the cans so that the cans will pass freely through the twister. In moving downwardly through the twister the cans are turned or oriented by the diagonally disposed surfaces indicated at 135, 136 in Fig. 8.

Fixed to the end of the section 112 adjacent the plain face 125 is an angle bar 138, and fixed to the end of the section 113 adjacent the plain face 127 is an angle bar 139. The angle bars 138, 139 are vertically disposed and spaced apart so as to align substantially with the lower portions of the angle bars 90 and 91. Between the angle bars 138, 139 is a slot 140 which is a continuation of the slot 92.

At a point adjacent to the feed valve 21, the conveyor 45 is formed with a stripper 141, by means of which the cans, after they have been turned by the twister 111, are transferred from the conveyor to the valve turret 31. As shown in Figs. 2 and 3, the upper end of the stripper 141 is secured to the lower portion of the twister 111 by bolts 142, and, as shown in Fig. 5, the lower portion of the stripper is anchored to the valve casing 22 by the bolts 14 heretofore referred to. The bracket 52 is connected by a bracket 143 to the feed valve housing 21, in the manner as shown in Fig. 3.

The stripper 141 (Fig. 14) is composed of two similarly formed sections 145, 146 which are spaced apart vertically so as to provide a slot 147 therebetween through which the studs 70 of the chain 48 pass in traveling downwardly through

the stripper. The angle bars 138, 139 depend from the twister 111 downwardly of the stripper 141 and are secured to the ends of the sections 145, 146. The construction and arrangement of the parts is such that a continuous trackway is provided in the fixed guide 71, the twister 111 and the stripper 141 for the chain 48, as shown best in Figs. 7 to 16, inclusive.

As illustrated in Figs. 5 and 14, the sections 145, 146 of the stripper are formed with parallel opposed inclined walls 148, 149 which extend downwardly from the bottom of the can twister toward the inlet opening 26 of the feed valve 21. The section 145 is formed with an end wall 150 and the section 146 is formed with an end wall 151. The end walls 150, 151 align substantially with the end walls of the pockets 33 of the valve turret 31 and prevent endwise shifting movement of the cans passing through the stripper to the valve turret. The construction of the parts is such that a clear smooth channel or canway is provided through which the cans are adapted to freely pass when being transferred from the conveyor to the feed valve 21. The wall 148 extends obliquely across the path of the studs 70, the upper portion of said wall being arcuate and the lower portion of said wall being substantially straight. The wall 148 has a can supporting surface 152, the contour of said surface being such that each can, as it approaches the inlet opening 26 is cammed laterally toward a pocket 33 of the turret 31 as the pocket moves into registry with the inlet opening 26. The canway in the twister 111 and in the stripper 141 is slightly larger than the cans so that the cans can travel toward the pockets 33 in the valve turret without interference. However, the width of the canway should not be of such extent that the cans will tip or cant endwise and become lodged at an angle with respect to the walls of the canway.

It will be understood that the can twister 111 of the present invention can be used either for cylindrical cans, as herein illustrated, or for rectangular cans.

In operation, after the cans have been filled and closed, they are delivered in a horizontal position by any suitable means to the upper flight 71 of the conveyor 45. When a can enters the conveyor it is engaged by the stud 70 which is behind it and the stud propels the can forwardly along the upper can supporting member 78. The cans are then directed by the can supporting member downwardly of the portions 75, 76, and as the cans pass through the arcuate portion 75 they rest upon the studs 70 which are disposed below them. The cans are carried down the vertical portion 76 of the conveyor in a substantially horizontal position with the longitudinal axes of the cans disposed substantially parallel with the longitudinal axes of the studs, and in case the cans are cylindrical in form there is a single line contact of the cans with the studs. Thus, from the point at which the cans are delivered to the conveyor to a point above the feed valve 21, the cans are propelled by the studs 70 of the conveyor chain 48, and during the travel of the cans downwardly toward the valve turret 31, the cans gravitate and rest upon or are supported by the studs and are lowered thereby through the spiral canway of the twister 111 and the canway of the stripper 141. During gravitation of the cans downwardly of the conveyor the movement of the cans through the twister and the stripper is always under the control of the studs 70. In moving through the twister 111 the cans

are turned in the manner heretofore described through an angle of approximately 90 degrees so that the longitudinal axis of each can will be disposed substantially parallel with the longitudinal axis of the canway of the stripper 141. Since the studs 70 are cylindrical in form and the cans 46 are cylindrical, the cans being turned by the twister 111 are rotated about a single point indicated at 154 in Figs. 8 to 12, inclusive.

The movement of the studs 70 in a downward vertical direction is in timed relation with the rotation of the feed valve turret 31, so that the can supporting surface 35 of a pocket 33 will align substantially with the upper surface of a stud 70, at the point said surfaces cross a line 15 passing horizontally through the center of the turret shaft 32, as shown in Fig. 5. Furthermore, the can being lowered by a stud 70 of the chain 48 engages the surface 152 of the stripper as soon as the can passes through the lower end of the twister, and due to the construction and arrangement of the parts, when the upper surface of the stud on which the can is supported is substantially aligned with the supporting surface 35 of a pocket, the can is pushed by the stripper off the end of the stud and enters the pocket, as indicated at 155, Figs. 5 and 6. In this way when the can moves obliquely across the stripper in a downward direction the can will be delivered on its side into a pocket of the turret without being dropped into the pocket, and due to the fact that the chain and the turret operate in timed relation the can is gradually lowered into a pocket of the turret valve as the surface 35 of the pocket and the stud 70 move down.

It will furthermore be noted that the vertical section of the conveyor provided by the twister 111 and the stripper 141 is disposed tangentially with respect to the periphery of the feed valve turret 31 and is arranged to convey cans rectilinearly downwardly in the same general direction as the direction in which the can supporting surfaces 35 of the pockets 33 of the valve turret 31 move past the inlet opening 26 of the feed valve so as to insure a smooth unbroken movement of the cans when the cans are transferred from the conveyor to the feed valve.

The disposition of the stripper 141 relative to the feed valve, and the manner in which the movement of the studs 70 in a downward vertical direction is in timed relation with the rotation of the feed valve turret 31, is such that each can is delivered on its side into a pocket. The stripper 141 thus constitutes means for intercepting a can carried by the conveyor and for gradually introducing the can into a pocket 33 of the turret whereby the can is transferred without shock or injury to the supporting surface 35 of the pocket which is moving downwardly past the inlet opening 26.

An advantage of the construction herein disclosed is that it provides an improved mechanism by which the gravitational speed of the cans moving through the can twister 111 is positively controlled. Another advantage is that the cans are turned through a predetermined angle from one position toward a desired position while supported on elements of a conveyor chain traveling at a predetermined speed. Still another advantage of the present invention is that the conveyor is so constructed that the chain and its studs are guided in the same relative position throughout the entire conveyor.

While in the drawings, by way of example, the can feeding mechanism of the present invention

has been shown as adapted for cooperation with a continuous pressure cooker, it will be apparent that the same may equally well be utilized in connection with other apparatus as will be obvious to those versed in the art.

What I claim and desire to protect by Letters Patent is:

1. A can feeding means comprising a guide having a can supporting surface and side walls provided with slots formed lengthwise and coextensive thereof, a conveyor chain arranged outside of the guide and disposed alongside one of the side walls thereof, said chain having can moving elements extending through the slotted side walls and arranged crosswise of the guide for moving cans lengthwise of the guide with the longitudinal center lines of the cans disposed at right angles to the line of travel, and a can twister for turning the cans from one position to another position, said can twister having a slot formed lengthwise thereof in alignment with the slotted side walls of said guide through which the can moving elements of said chain travel in a straight line in the same relative position as the position of said elements in the guide.

2. A can feeding mechanism comprising a fixed guide having a can supporting surface and side walls provided with slots formed lengthwise and coextensive thereof, a conveyor chain arranged outside of the guide and disposed alongside of one of the side walls thereof, said chain having can moving elements extending through the slotted side walls and arranged crosswise of the guide for moving cans disposed in a predetermined position on said supporting surface lengthwise of the guide, and means through which the cans and the can moving elements of said chain travel for turning the cans through a predetermined angle from one position to another position, the can moving elements of said chain passing through said can turning means in the same relative position as the position of said elements in the guide.

3. Mechanism for feeding cans to a feed valve rotating in a vertical plane about a horizontal axis and having peripheral pockets each adapted to receive a can with its cylindrical axis parallel to that of the feed valve, comprising a conveyor having a portion disposed to elevate cans in a plane perpendicular to the plane of rotation of said valve, said conveyor including a can support having slotted sides and a conveyor chain arranged at one side thereof with lateral pins extending through the slotted sides of said support for controlling the movement of containers along said support, said conveyor having a vertically disposed portion for lowering the cans toward the mouth of said feed valve, said vertically disposed portion of the conveyor having spirally disposed inner surfaces for effecting turning of the cans from a position perpendicular of the axis of rotation of said valve to a position parallel thereto as the cans move toward said valve, said conveyor chain pins having single line contact with said cans as they turn between said spirally disposed surfaces so that the cans freely turn therebetween for admittance into the mouth of said feed valve in timed relation with registration of the peripheral pockets therewith.

4. An arrangement for delivering cans into a rotary feed valve of the type having peripheral pockets adapted to receive cans with their axis parallel to the axis of rotation of the feed valve and wherein said valve turns about a horizontal

axis, said arrangement comprising a channel having an ascending run adapted to guide cans with their axes at right angles to said horizontal axis of rotation to a level above said valve, a descending run adapted to guide cans from a level above said valve to a point tangentially of said valve at the level of said axis of rotation, spiral guide surfaces arranged within said descending run to turn the cans from a position wherein their axes are at right angles to the axis of rotation of the valve to a position in which their axes lie parallel to said axis of rotation, a conveyor chain arranged to move along both the ascending and the descending run of said channel, and can-engaging elements carried by said chain and arranged to protrude into said channel to propel the cans through said ascending run and to retard their descent through said descending run.

5. A can feeding mechanism comprising a helical guide portion having can supporting surfaces extending from an upper to a lower level and arranged to turn a can from one position to another as the can moves along said helical guide portion, said guide portion having straight slots formed to extend lengthwise in opposite sides thereof, a flexible conveyor element arranged for lengthwise movement outside of the guide, a can engaging element mounted on said conveyor element to extend through said slots for engaging a can within said guide to control movement of the can through the helical guide portion, and power drive means mounted to advance said conveyor element and the can engaging element thereon lengthwise of said helical 35 guide portion.

6. Can feeding mechanism comprising a can guide having a straight portion and a continuing helically twisted portion, a conveyor element mounted to travel lengthwise of said guide throughout both the straight and twisted portions thereof, a plurality of flight members mounted on said conveyor element to extend transversely of said guide and adapted to engage and control the movement of cans lengthwise of said guide throughout both of said guide portions, the twisted portion of said guide being slotted in a straight line lengthwise thereof to receive said flight members for guided travel along a planiform path substantially bisecting the twisted portion of said guide and extending lengthwise thereof, and power drive means connected to drive said conveyor element and the flight members mounted thereon along said guide at a controlled rate of speed.
